UNITED STATES PATENT OFFICE

2,650,474

SASH GATE

Jacques Jean Emile Mesnager, Paris, France

Application March 10, 1948, Serial No. 14,039
In France March 12, 1947

10 Claims. (Cl. 61—28)

1

It was disclosed that, in order to easily move the operating mechanism of sash gates, it might be used fluid-sheet rest elements interposed between the gates and their rest surface, the rollers and slide bars generally used being thus replaced by fluid sheets under pressure; with such a device, there are no more important frictions encountered as with an ordinary device, whenever the gate is operated.

The main difficulties that are encountered in the design of fluid-sheet rest sliding apparatus are as follows:

1. Permitting the movable system to incline according to variations of the pressure exerted upon the different parts thereof.

2. Providing for a permanent fluid-tight joint between the rest surface and the movable system in the course of the displacement in spite of the unavoidable inequalities and warp of the rest surface, which is liable to be deformed just the same as the movable system by the action of the forces to which they are subjected. This results in variations in the distance between the movable system and the rest plate which are hardly consistent with a correct functioning of the flexible joint.

The present invention has for its object an improved fluid-sheet rest device with which both main aforementioned inconveniences are removed by the provision, between the rest surface and the movable system, of an intermediate element or frame that carries the sealing member and which is movable with respect to the movable system. Preferably, said frame should possess a certain flexibility. It will thereby be capable of laying itself against the rest surface and of conforming its shape in spite of the inequalities and deformations of the latter, the purpose of the sealing member being merely to offset small local inequalities.

Said intermediate frame is connected with the movable system through the medium of a flexible membrane such as a sheet-metal bellow, a reinforced elastic fabric, a leather sleeve, etc., so as to provide a receptacle containing the liquid under pressure.

In order to keep the thickness of the fluid sheet unchanged in spite of any leakage that may occur notably at the edges, it is necessary to feed said sheet with the aid of a compressor which may be stationary or carried by the movable system.

The admission of the fluid is controlled by one or several valves in dependence on the distance between the movable system to the fixed rest. The interposition of fluid-operated jacks de-

signed for large variations in the said distance makes the achievement of this arrangement particularly easy, said hydraulic jacks being constituted by the fluid sheets themselves.

5 Where the stroke of the movable system exceeds its length the fluid may be fed through a series of fixed nozzles provided each with a valve controlled in the aforesaid manner and adapted to close automatically as soon as the nozzle is no longer covered.

The improvements according to the invention will be described hereinafter, reference being had to the appended drawings in which:

Figure 1 is a front view of a sash gate.

Figure 2 is a side view of the same.

Figure 3 is a horizontal section of a fluid sheet element.

Figure 4 is a side view of said element, parts being broken away.

Figure 5 is a sectional view taken on line V—V in Fig. 4.

Figure 6 is a horizontal section of an alternative construction of the element.

25 Referring now to Fig. 1, a gate 1 is movable with respect to a stonework 10 on which it is rested through the medium of a pair of fluid sheets 2 and a pair of rollers 3, one of them at either side of the gate. Rollers 4 rested on a frame 5 are provided to compensate for the tendency of the gate to tilt when the forebay is empty. The gate is operated with the aid of a flexible ribbon 6 trained over a pulley 7 the shell 8 of which is secured to the upper end of the gate 1. The flexible ribbon 6 may be trained over a simple smooth driving drum.

30 The gate 1 carries a frame 11 rigid therewith and connected with a further frame 12 through the medium of a ring-shaped flexible membrane 13. Said membrane is pressed against the frame 11 by a clamping frame 21 pressed thereon by screws 14. Similarly, the membrane 13 is pressed against the frame 12 by a clamping frame 22 pressed thereon by screws 15. The same clamping frame 22 serves to secure a ring shaped

45 resilient, e. g. rubber pad 16 against the frame 12 to seal the joint between a smooth rest surface 17 and the inside of the element. Said pad 16 is pressed against the rest surface 17 by the pressure exerted by the fluid upon the side 16' of the same.

50 The frames 11 and 12 are constituted by the edges of plates 31 and 32 interconnected by a flexible plate 18 secured thereto by means of bolts 19, 20, by which flexible plate the frame 12 is enabled to move with the frame 11 without hin-

55

dering the displacement of either of said frames towards or away from the other. Plate 32 carries girders 23 adapted to take a rest on the surface 17 whenever the inner pressure of the fluid sheet becomes abnormally low (as shown in the upper portion of Fig. 3). Apertures 33 through plate 32 permit the fluid to flow from one side to the other of plate 32. A tight space of variable volume and shape comprising two rooms in communication through the apertures 33 is thus provided between the stonework 10 and the gate 1, on either side of frame 12 and plate 32. The side-wall of one of these rooms is constituted by the ring-shaped membrane 13, the side-wall of the other room is constituted by the ring-shaped pad 16.

Preferably, the frames 11 and 12 as well as the presser frames 21 and 22 have round upper and lower ends (Fig. 5). In this manner the flexible membrane 13 is able to surround said frames while assuming a cylindrical shape at either vertical side of said frames and a toric shape at the top and bottom edges of the same.

The flexible membrane 13 is constituted by an elastic rubber, buna or like membrane or simply by a flexible impervious membrane and may be reinforced with wires in the planes at right angles to the gate.

The flexible membrane may have a Z-like section as shown in Fig. 4 or be plane as in the device illustrated in Fig. 6; in the latter case the frame 34 of gate 1 and the intermediate frame 35 connected with same through membrane 36 secured between the shaped members 37 and 39 provide a resilient cushion filled with a fluid. The frame 35 and the plate 32 rigid therewith are rested here on the rest surface 17 through pads 40.

The pressure on the liquid present in the fluid sheet is kept by a compressor at such a value that the thickness of the said sheet shall remain substantially constant. This result is obtained automatically by means of a spring-valve 24 adapted to open or close the pipe 25 leading from the compressor to an orifice 26 in the rest surface 17 and the shank 27 of which engages an angle iron 38 rigid with the frame 11 and the gate.

As the frame 11 moves towards the rest surface 17 the shank 27 is pushed by the angle iron 38 on which its end is rested; the spring-valve 24 is thus lifted and the pressure in the fluid sheet is increased until the frame stands at the desired distance from the rest surface. Conversely, as the frame 11 moves away from the rest surface, the valve 24 comes again into engagement with its seat.

It should be understood that the embodiments described hereinbefore and illustrated in the appended drawing are given for the purpose of exemplification and by no means of limitation and that many modifications may be made without thereby departing from the scope of the invention. For example, the rest surface may be on the gate and the intermediate plate so as the membrane may be attached to the immovable work along which the movable system is shifted. The arrangements described may also be used for other purposes than the translation of water gates; thus, for example a plurality of fluid elements may be used for the launching of a ship down its ways.

What I claim as my invention and desire to secure by Letters Patent is:

1. A water gate comprising an immovable work having a smooth surface, a movable gate mounted on said work for shifting motion parallel with

said surface, a ring-shaped deformable membrane tightly attached to the movable gate in front of the smooth surface of the work, a frame attached to said ring-shaped membrane all around the same between the movable gate and the smooth surface of the work in a position nearly parallel with said surface, a ring-shaped resilient pad attached to the frame all around the same and having a tight connection with said deformable membrane, said ring-shaped pad having a sliding and tight contact along a ring-shaped line with the smooth surface of the work, a tight space of variable volume and shape having said ring-shaped membrane and pad for their side-walls being thus provided between said work and said movable gate, means for admitting a fluid into said tight space and for keeping said fluid under pressure in said tight space, whereby providing for the movable gate a resilient fluid-containing hollow support attached thereto and having a sliding resting contact with the smooth surface of the work, and means for sliding said movable gate and said resilient support along said smooth surface of said work.

2. A water gate comprising an immovable work having a smooth surface, a movable gate mounted on said work for shifting motion parallel with said surface, a ring-shaped deformable membrane tightly attached to the movable gate in front of the smooth surface of the work, a frame attached to said ring-shaped membrane all around the same between the movable gate and the smooth surface of the work in a position nearly parallel with said surface, a ring-shaped resilient pad attached to the frame all around the same and having a tight connection with said deformable membrane, said ring-shaped pad having a sliding and tight contact along a ring-shaped line with the smooth surface of the work, a tight space of variable volume and shape having said ring-shaped membrane and pad for their side-walls being thus provided between said work and said movable gate, means for admitting a fluid into said tight space and for keeping said fluid under pressure in said tight space, whereby providing for the movable gate a resilient fluid-containing hollow support attached thereto and having a sliding resting contact with the smooth surface of the work, and means for sliding said movable gate and said resilient support along said smooth surface of said work.

3. A water gate comprising an immovable work having a smooth surface, a movable gate mounted on said work for shifting motion parallel with said surface, a ring-shaped deformable membrane tightly attached to the movable gate in front of the smooth surface of the work, a frame attached to said ring-shaped membrane all around the same between the movable gate and the smooth surface of the work in a position nearly parallel with said surface, a ring-shaped resilient pad attached to the frame all around the same and having a tight connection with said deformable membrane, said ring-shaped pad having a sliding and tight contact along a ring-shaped line with the smooth surface of the work, a tight space of variable volume and shape having said ring-shaped membrane and pad for their side-walls being thus provided between said work and said movable gate, means for admitting a fluid into said tight space and for keeping said fluid under pressure in said tight space, whereby providing for the movable gate a resilient fluid-containing hollow support attached thereto and having a sliding resting contact with the smooth surface of the work, and means for sliding said movable gate and said resilient support along said smooth surface of said work, a rest member on said movable gate, adapted for entering into resting contact with the frame whenever the distance between the movable gate and the frame decreases down to a predetermined value, and a rest member firm with said frame and adapted for entering into resting contact with the work whenever the distance between the frame and the work decreases down to a predetermined value.

4. A water gate comprising an immovable work having a smooth surface, a movable gate mounted on said work for shifting motion parallel with said surface, a ring-shaped deformable membrane tightly attached to the movable gate in front of the smooth surface of the work, a frame attached to said ring-shaped membrane all around the same between the movable gate and the smooth surface of the work in a position nearly parallel with said surface, a ring-shaped resilient pad attached to the frame all around the same and having a tight connection with said deformable membrane, said ring-shaped pad having a sliding and tight contact along a ring-shaped line with the smooth surface of the work,

a tight space of variable volume and shape having said ring-shaped membrane and pad for their side-walls being thus provided between said work and said movable gate, means for admitting a fluid into said tight space and for keeping said fluid under pressure in said tight space, whereby providing for the movable gate a resilient fluid-containing hollow support attached thereto and having a sliding resting contact with the smooth surface of the work, self-operating means for cutting the admission of fluid into said tight space whenever the distance between the movable gate and the smooth surface of the work comes to exceed a predetermined value, and means for sliding said movable gate and said resilient support along said smooth surface of said work.

4. A resilient support for providing a sliding resting contact between a first heavy mass and a second heavy mass having a smooth surface and capable of relative shifting motion parallel with said smooth surface with regard to the first heavy mass, said support comprising a frame located between both heavy masses in front of the smooth surface of the second heavy mass and in a position nearly parallel with said smooth surface, a ring-shaped deformable membrane attached to said frame all around the same and having a tight connection with said first heavy mass along a ring-shaped line located in front of said frame, a ring-shaped resilient pad attached to the frame all around the same and having a tight connection with said deformable membrane, said ring-shaped pad having a sliding and tight contact along a ring-shaped line with the smooth surface of the second heavy mass, a tight space of variable volume and shape having for side-walls said ring-adapted membrane and pad being thus provided between both heavy masses and means for admitting a fluid into said tight space and for keeping said fluid under pressure in said space, whereby providing for the first heavy mass a resilient fluid-containing hollow support attached thereto and having a sliding resting contact with the smooth surface of the second heavy mass.

5. A resilient support for providing a sliding resting contact between a first heavy mass and a second heavy mass having a smooth surface and capable of relative shifting motion parallel with said smooth surface with regard to the first heavy mass, said support comprising a frame located between both heavy masses in front of the smooth surface of the second heavy mass and in a position nearly parallel with said smooth surface, a ring-shaped deformable membrane attached to said frame all around the same and having a tight connection with said first heavy mass along a ring-shaped line located in front of said frame, a ring-shaped resilient pad attached to the frame all around the same and having a tight connection with said deformable membrane, said ring-shaped pad having a sliding and tight contact along a ring-shaped line with the smooth surface of the second heavy mass, a tight space of variable volume and shape having for side-walls said ring-shaped membrane and pad being thus provided between both heavy masses, means for admitting a fluid into said tight space and for keeping said fluid under pressure in said space, whereby providing for the first heavy mass a resilient fluid-containing hollow support attached thereto and having a sliding resting contact with the smooth surface of the second heavy mass, a rest member on said first heavy

mass, adapted for entering into resting contact with the frame whenever the distance between said first heavy mass and said frame decreases down to a predetermined value, and a rest member firm with said frame and adapted for entering into resting contact with the second heavy mass whenever the distance between said second heavy mass and said frame decreases down to a predetermined value.

10 6. A water gate comprising an immovable work having a smooth surface, a movable gate mounted on said work for shifting motion parallel with said surface, a plate having a flexible connection with said movable gate and located between said movable gate and said work, in front of the smooth surface of the work and in a position nearly parallel therewith, said plate being provided with apertures, a ring-shaped deformable membrane having a tight connection with said plate all around the edge thereof and with the movable gate along a ring-shaped line in front of said plate, providing thus a first room of variable volume between said plate, said gate and said membrane, a ring-shaped resilient pad having a tight connection with said plate along a ring-shaped line and having a sliding and tight contact along a ring-shaped line with the smooth surface of the work, a second room of variable volume in communication with the first said room through the apertures of the plate being thus provided between said work, said plate and said pad, means for admitting a fluid into said communicating rooms and for keeping said fluid under pressure in said rooms, whereby providing for the movable gate a resilient fluid-containing hollow support attached thereto and having a sliding resting contact with the smooth surface of the work, and means for sliding said movable gate and said resilient support along said smooth surface of said work.

7. A water gate comprising an immovable work having a smooth surface, a movable gate mounted on said work for shifting motion parallel with said surface, a plate having a flexible connection with said movable gate and located between said movable gate and said work, in front of the smooth surface of the work and in a position nearly parallel therewith, said plate being provided with apertures, a ring-shaped deformable membrane having a tight connection with said plate all around the edge thereof and with the movable gate along a ring-shaped line in front of said plate, providing thus a first room of variable volume between said plate, said gate and said membrane, a ring-shaped resilient pad having a tight connection with said plate along a ring-shaped line and having a sliding and tight contact along a ring-shaped line with the smooth surface of the work, a second room of variable volume in communication with the first said room through the apertures of the plate being thus provided between said work, said plate and said pad, means for admitting a fluid into said communicating rooms and for keeping said fluid under pressure in said rooms, whereby providing for the movable gate a resilient fluid-containing hollow support attached thereto and having a sliding resting contact with the smooth surface of the work, means for sliding said movable gate and said resilient support along said smooth surface of said work, a rest-member on said movable gate adapted for entering into resting contact with the plate whenever the distance between said plate and said movable gate decreases down to a predetermined value, and a rest-member on

said plate adapted for entering into resting contact with the work whenever the distance between said work and said plate decreases down to a predetermined value.

8. A water gate comprising an immovable work having a smooth surface, a movable gate mounted on said work for shifting motion parallel with said surface, a plate having a flexible connection with said movable gate and located between said movable gate and said work, in front of the smooth surface of the work and in a position nearly parallel therewith, said plate being provided with apertures, a ring-shaped deformable membrane having a tight connection with said plate all around the edge thereof and with the movable gate along a ring-shaped line in front of said plate, providing thus a first room of variable volume between said plate, said gate and said membrane, a ring-shaped resilient pad having a tight connection with said plate along a ring-shaped line and having a sliding and tight contact along a ring-shaped line with the smooth surface of the work, a second room of variable volume in communication with the first said room through the apertures of the plate being thus provided between said work, said plate and said pad, a duct in the fixed work, disengaging through the smooth surface thereof within the ring-shaped contact line of the resilient pad, thereby adapted for admitting a fluid into said second room as also into the first room through the apertures of the plate, means for keeping said fluid under pressure in said rooms, whereby providing for the movable gate a resilient fluid-containing hollow support attached thereto and having a sliding resting contact with the smooth surface of the work, and means for sliding said gate and said resilient support along said smooth surface of said work.

9. A resilient support for providing a sliding resting contact between a first heavy mass and a second heavy mass having a smooth surface and capable of relative shifting motion parallel with said smooth surface with regard to the first heavy mass, said support comprising a deformable connecting-member attached to the first mass in front of the second mass, a plate attached to said connecting-member and located between both heavy masses in front of the smooth surface of the second heavy mass and in a position nearly parallel with said smooth surface, a ring-shaped deformable membrane having a tight connection with said plate along a ring-shaped line, and with the first heavy mass along a ring-shaped line located in front of said plate, providing thus a first room of variable volume between said first heavy mass, said plate and said membrane, a ring-shaped resilient pad having a tight connection with said plate along a ring-shaped line,

said ring-shaped pad having a sliding and tight contact along a ring-shaped line with the smooth surface of the second heavy mass, providing thus a second room of variable volume between said second heavy mass, said plate and said pad, and means for admitting a fluid into both said rooms and for keeping said fluid under pressure in said rooms, whereby providing for the first heavy mass a resilient fluid-containing hollow support attached thereto and having a sliding resting contact with the smooth surface of the second heavy mass.

10. A resilient support for providing a sliding resting contact between a first heavy mass and a second heavy mass having a smooth surface and capable of relative shifting motion parallel with said smooth surface with regard to the first heavy mass, said support comprising a deformable connecting-member attached to the first mass in front of the second mass, a plate attached to said connecting-member and located between both heavy masses in front of the smooth surface of the second heavy mass and in a position nearly parallel with said smooth surface, a ring-shaped deformable membrane having a tight connection with said plate along a ring-shaped line, and with the first heavy mass along a ring-shaped line located in front of said plate, providing thus a first room of variable volume between said first heavy mass, said plate and said membrane, a ring-shaped resilient pad having a tight connection with said plate along a ring-shaped line, said ring-shaped pad having a sliding and tight contact along a ring-shaped line with the smooth surface of the second heavy mass, providing thus a second room of variable volume between said second heavy mass, said plate and said pad, means for admitting a fluid into both said rooms and for keeping said fluid under pressure in said rooms, whereby providing for the first heavy mass a resilient fluid-containing hollow support attached thereto and having a sliding resting contact with the smooth surface of the second heavy mass, a rest member on said first heavy mass adapted for entering into resting contact with the plate whenever the distance between said plate and said first heavy mass decreases down to a predetermined value, and a rest member on the plate, adapted for entering into resting contact with the second heavy mass whenever the distance between said second heavy mass and said plate decreases down to a predetermined value.
